UNITED STATES PATENT OFFICE.

EMERSON A. BOLEN, OF MORRIS, ILLINOIS, ASSIGNOR TO NORTH WESTERN NOVELTY COMPANY, OF MORRIS, ILLINOIS, A CORPORATION OF ILLINOIS.

DESIGN FOR A CASING FOR VENDING-MACHINES.

43,690.

Specification for Design.

Patented Mar. 11, 1913.

Application filed November 25, 1912. Serial No. 733,545. Term of patent 7 years.

To all whom it may concern:

Be it known that I, EMERSON A. BOLEN, a citizen of the United States, residing at Morris, in the county of Grundy and State of Illinois, have invented a new, original, and ornamental Design for a Casing for Vending-Machines, of which the following is a specification, reference being had to the accompanying drawing, wherein I have shown my new design.

The figure is a perspective view.

I claim:

The ornamental design for a casing for vending machine, as shown.

EMERSON A. BOLEN.
